UNITED STATES PATENT OFFICE

JOHN A. MAKER, OF DULUTH, MINNESOTA

REVERSIBLE WASTE RECEIVER

Application filed October 14, 1927. Serial No. 226,245.

This invention relates to a waste receptacle and has special reference to one particularly adapted for use by dentists, the principal object being to provide a more convenient and economical waste receptacle than heretofore known.

Another object is to provide one susceptible of longer use without change than similar devices now employed.

10 Other objects and advantages of the novel structure will appear in the further description thereof.

Referring now to the accompanying drawing, forming part of this application, and 15 wherein like reference characters indicate like parts:

Figure 1 is a plan view of the preferred form of paper blank used in the construction of the improved receptacle;

20 Figure 2 is a perspective view of the receptacle; partly assembled.

Figure 3 is a perspective view of a glass container holding one of the receptacles; and

25 Figure 4 is a similar view of a modified form of a reversible unit.

The blank comprises the major elongated body portion including the two ends 1 and 2, the two sides 3 and 4, and the holding flap 5. Transverse one end of this portion and in-

30 tegral with the end 1 is a right angular extension 6, foldable on the lines indicated at 7 and 8 and the space intermediate of which, indicated at 9, forming when folded one of the partition walls which divide the receptacle 35 into two equal parts or chambers. Upon the opposite side of the portion 1 is formed the flap 10.

Contiguous with the portion 2, integral therewith and parallel with the extension 6 is 40 a similar extension 11, also foldable upon the lines 12 and 13, the space between which, indicated at 14, forming a like central partition which when the receptacle is folded abuts the partition 9, the object of which is to reinforce said partition wall by making it double, preventing the liability of same becoming 45 dislocated when one end of the receptacle is filled before the other, and further to prevent any leakage from one portion of the receptacle to the other. On the opposite side of the

portion 2 to the extension 11 is formed the flap 15, similar and for a like purpose as the flap 10, while intermediate of these two flaps 10 and 15 and contiguous with the portion 3 is the portion 16, foldable as at 17 forming 55 the flap 18 and which portion 16 forms another side of the assembled receptacle. Contiguous with the portion 4 is a like side wall extension 19, foldable as at 20, forming the flap 21, similar to the flap 18 and functioning 60 in a like manner upon the opposite side when the receptacle is folded, resulting in a double chambered rectangularly shaped receptacle as clearly shown in Figure 2; there being cross-like slits indicated at 22 and 23 in the 65 opposite ends thereof.

While this receptacle may be used independently it is preferred to mount same with-in a more weighty object, such as a glass or bakelite container illustrated at 24 and 70 formed with a through rectangularly shaped bore in which the paper receptacle previously described tightly fits. To facilitate the convenient change of the waste receiver it is obvious that the bore of the receptacle may be 75 slightly tapered, or the paper receptacle itself made slightly smaller at one end than at the other.

By such an assemblage it is apparent that I have provided a waste receptacle occupying 80 little if any more room than the ordinary one used, but capable of twice the service with equal sanitation, the double functioning of the device being accomplished by its reversi- 85

In Figure 4 I have illustrated a modified form of the invention, the same comprising a holder or block of glass or the like, common to a plurality of waste receptacles which may either be double as previously described or 90 single as are now commonly used and if the latter placed therein oppositely that is the receiving end of one in the same side with the closed end of the other so that in its use a mistake will not readily occur in placing 95 waste material therein; but in the event of my improved double receptacle being used therein accommodation for four different batches of waste material will be afforded.

Having thus described my invention, what 100

I claim and desire to secure by Letters Patent, is:

1. A reversible waste receiver of the class described comprising a receptacle having chambers therein each accessible from one end only of the receiver.
2. A reversible waste receiver of the class described having a plurality of chambers therein separated by a transverse wall and an entranceway in each end of the receiver to its adjacent chamber.
3. A rectangular waste receiving unit of the class described having two chambers therein arranged in tandem and accessible from opposite ends of the unit.
15. 4. The combination with a reversible waste receiver, of a double transverse partition wall centrally thereof forming tandem chambers each accessible through its outermost end.
20. 5. A blank for a double chambered receptacle of the character described comprising a major elongated body portion embodying both ends and two sides of the receptacle, another side of the receptacle formed integral with the body portion, the other side of the receptacle formed integral with the opposite side of the body portion, double partitions formed integral with one side of the body portion, and flaps formed integral with the blank for the purpose described.
30. In testimony whereof I affix my signature.
JOHN A. MAKER.
